UNITED STATES PATENT OFFICE.

CHARLES N. TRUMP, OF WILMINGTON, DELAWARE.

APPARATUS FOR MAKING COKE AND GAS.

SPECIFICATION forming part of Letters Patent No. 436,882, dated September 23, 1890.

Application filed February 2, 1888. Serial No. 262,695. (No model.)

To all whom it may concern:

Be it known that I, CHARLES NEWBOLD TRUMP, a citizen of the United States, residing at Wilmington, in the county of New 5 Castle and State of Delaware, have invented certain new and useful Improvements in Apparatus for Making Coke and Gas, of which the following is a specification.

My invention relates to an improved arrangement and combination of appliances for making coke and of conserving the rich hydrocarbon gases given off from the coal being coked.

Heretofore coking-ovens have chiefly been heated by burning the rich gases driven off from the coal in the process of coke-making in the tops of bee-hive ovens or in the furnaces and flues of the so-called "Belgian" coke-ovens.

20 The principal object of my present invention is to reduce the cost of production of coke, gas, and other products of the destructive distillation of coal by substituting cheaply made water and producer gas, or a mixture of them, for the rich hydrocarbon gases heretofore burned in heating coking-ovens by introducing said gas from the producer or generator in a heated condition directly into the furnace and flues of said coking-ovens and burning it, thereby materially economizing in fuel and conserving the rich hydrocarbon gases given off from the coal being coked for admixture with natural gas or other fuel gases, in order to impart to them the characteristic 35 odor of coal-gas, and also affording additional heat-giving properties.

The characteristic features of my invention will be more fully understood from the following description, taken in connection with 40 the accompanying drawing, showing, partly in section and partly in elevation, a plant of my improved construction.

Referring to the drawing, C C are the coke-ovens.

45 A is the gas-producer; B, the regenerator; F, the cooler, and G the scrubber.

The gas-connections and details will be hereinafter described.

The gas-producer A may be any of the well-known forms of producer or water gas generators. Preference, however, is given to a

Taylor producer provided with a revolving bottom.

The coke-oven C may be of either the Carves, Appolt, or bee-hive forms.

The coke-oven shown is of the Simon-Carves type, in which the air to support combustion in the furnace and flues is drawn through a duct in contact with the flues for conducting the escaping products of combustion.

The operation of the apparatus is as follows: A fire is started in the producer or generator A, and anthracite, buckwheat coal, culm, or other fuel charged in until a sufficient quantity is had therein. Air is forced in through 65 the pipe d by a jet of steam, and the resultant gases, being a mixture of producer and water gas, conveyed by pipes a and a', which are preferably covered with suitable material to retain the initial heat, to the furnace of 70 the coke-oven C, where they are ignited by fire previously started on the grate of the furnace. Air heated by the escaping products of combustion is supplied to burn the gas or gases in the furnace and flues of the 75 oven, as is well understood in the practice of the Simon-Carves system.

The coke-oven C is provided with a furnace C² and with a pipe a', leading from the gas producer or generator into the furnace 80 of said oven. When sufficiently heated, the coke-oven is charged through openings, as C³, in the top thereof, the coal leveled, and all openings properly closed and luted.

When bee-hive or rectangular shaped ovens 85 with bottom flues (through which the rich gases are exhausted, as in Jamison's system of coke-making,) are used, the producer or water gas from the producer or generator A would be conducted to the tops of the ovens 90 and burned above the surface of the coal evenly spread onto the bottom. After coking is complete the charge may be raked out and quenched.

In the drawing is shown a system which is 95 especially adapted for use when bituminous coal is availed of, and in which by-products, as ammoniacal liquor and tar, are to be separated from the gas generated in the producer A.

The operation is as follows: The producer or generator A being charged and the charge

ignited, air is forced through the pipe *d* by a jet of superheated steam, and the resultant gases passing through the regenerator B, the cooler F, scrubber G, and the pipes, as shown, 5 deposit ammoniacal liquor and tar, which are lead to proper receptacles. From the outlets of the scrubber G suitable pipes *g*, *i*, *j*, and *k* are provided to conduct the cooled gases either to a purifier and gas-holder (not shown) 10 or to the base of the regenerator B. As the gas flows through the regenerator B around the zigzag pipes through which the hot gases from the producer or generator A are passing, it takes up a large proportion of the initial heat, conveying it through the pipes *a'* and *a''* to the furnace of the coke-ovens C C, where the gas burns more rapidly than if not heated. In fact, producer gases do not easily 15 ignite if cold.

20 The great merit of the arrangement of apparatus as hereinbefore described is that most

of the initial heat of generation is utilized in reheating the cooled gases, which, being conducted to the furnace and meeting hot air, are readily consumed under the most favorable conditions.

Having thus described the nature and objects of my invention, what I claim as new, and desire to secure by Letters Patent, is—

The combination of a gas-generator, a coke-oven, a regenerator, a cooler, a scrubber, and gas-connections extending from the generator through the regenerator, cooler, and scrubber, and back through the regenerator to the furnace of the coke-oven, substantially 30 as and for the purposes set forth.

In testimony whereof I affix my signature in presence of two witnesses.

CHAS. N. TRUMP.
